UNITED STATES PATENT OFFICE.

ROBERT H. PITTMAN, OF HONESDALE, PENNSYLVANIA, ASSIGNOR TO T. B. CLARK & CO., OF HONESDALE, PENNSYLVANIA.

DESIGN FOR A CUT-GLASS DISH.

No. 40,051.

Specification for Design.

Patented June 15, 1909.

Application filed April 20, 1909. Serial No. 491,200. Term of patent 7 years.

To all whom it may concern:

Be it known that I, ROBERT H. PITTMAN, a citizen of the United States, residing at Honesdale, in the county of Wayne and State of Pennsylvania, have invented a new, original, and ornamental Design for a Cut-Glass Dish, reference being had to the accompanying drawing, in which the figure is an inverted plan view of a cut-glass dish, showing my new design.

I claim:

The ornamental design for a cut glass dish, as shown.

ROBERT H. PITTMAN.
